UNITED STATES PATENT OFFICE.

WILLIAM SALWAY, OF WINTON PLACE, OHIO.

ATTACHMENT FOR STEAM-ROLLERS.

SPECIFICATION forming part of Letters Patent No. 743,336, dated November 3, 1903.

Application filed January 4, 1902. Serial No. 88,402. (No model.)

To all whom it may concern:

Be it known that I, WILLIAM SALWAY, a citizen of the United States, and a resident of Winton Place, in the county of Hamilton and State of Ohio, have invented certain new and useful Improvements in Attachments for Steam-Rollers, of which the following is a specification.

The several features of my invention and the various advantages resulting from their use conjointly or otherwise will be apparent from the following description and claims.

In the drawings making a part of this specification, and in which similar letters of reference indicate corresponding parts, Figure 1 is a view in perspective of a machine constructed to receive my improvements and with which my improvements are combined, my improvements being also illustrated by said machine. Fig. 2 is a side elevation of the adjacent wheel and of certain details of parts of my improvements, the wheel being partially broken away to the better enable these details to be seen. Fig. 3 is a rear view of the machine and of my improvements with the following exceptions, viz: that the wheel at the left-hand side is nearly all omitted and that a part of the right-hand wheel is broken away to the better disclose certain parts belonging to my improvements. Fig. 4 is a side elevation of the locking-pin. Fig. 5 is a detail illustrating the preferred mode of holding the free end of the wire rope when the latter is out of use. Fig. 6 is a sectional detail of the said means for holding the free end of the wire rope to the pulley. Fig. 7 is an elevation of the hook and a section of the nut to carry into effect the fastening of the free end of this rope. Fig. 8 is a plan view of the rear end of the machine, showing the preferred means for holding the shives for guiding the wire rope and the mode of connecting such means to the rear of the machine. Fig. 9 is an outside elevation of the driving-wheel, which is on the left hand of the machine, a portion of which wheel is shown at the left in Fig. 3. Parts of the wheel in this Fig. 9 are broken away to the better show other portions of the wheel and that discal piece or wheel behind the driving-wheel which is fixed to the driving-shaft. Fig. 10 is a view at the rear edge of the wheel shown in Fig. 9. Parts of the

wheel and of the tank are broken away to show the parts beyond. The hub of the driving-wheel and the discal piece or wheel are each shown in vertical central section. Fig. 11 is a side elevation of the locking-pin.

A indicates the boiler, B the smoke-stack, and C the coal-box or tender.

D indicates the engine and its accessory and supplemental parts.

E indicates conventionally the mechanism which operates the forward wheels F and includes the chains F². Such mechanism is for the most part located on the other side of the engine and is not seen; but a wheel E² for causing such mechanism to operate said wheels F through the mechanism of the chains F² is shown.

G indicates the driving-wheels, preferably provided, as shown, with a broad peripheral tread. H indicates the axle or shaft on which said wheels are concentrically located and whereby they may be driven. The wheels are connected to this shaft H in such a manner that they can be unlocked therefrom or locked thereto in a prompt and expeditious manner. A preferred mode for accomplishing such locking and unlocking is as illustrated—namely, fixed to the wheel G is a hub-piece G². This hub-piece and its wheel are loose on the shaft H. Fixed to the shaft H is a crank-piece H², preferably of a discal form, as shown. There is a hole, as G³, in the hub-piece G² and a series of holes, as H³, in the discal piece H². These holes in discal piece H² are set in the line of a circle, and each will successively come into alignment with the hole G³ in the crank-piece G² as the axle H and its discal piece H² are rotated or as the crank-piece G² is revolved. A locking-pin H⁴ is present and when passed through the hole G³ of the crank-piece G² and into a corresponding hole H³ of the discal piece H² will lock the wheel G and the discal piece H², and hence lock the wheel to the shaft. In this way the driving-wheels can be quickly and securely locked to the shaft H and also be as quickly unlocked when this becomes desirable.

The object of having a series of holes in the discal piece H² is when the wheel has been unlocked from the shaft to enable a hole of this discal piece to be brought opposite the

hole of the hub-piece G^2 without much rotation of the shaft. Thus the wheel G can be locked to the shaft without much rotation of the shaft H or of the wheel G , which may 5 have first been locked to the shaft. There is a locking-pin H^4 for the driving-wheel G and discal or crank piece on the one side and another locking-pin for the driving-wheel and its adjacent discal piece or wheel on the 10 other. While I could make both of these discal pieces pulleys, it is usually unnecessary to do so. I therefore make one of these discal pieces as a pulley or spool and provide it with a peripheral groove H^5 . Thus in the 15 illustrative drawings I provide the discal piece H^2 with such peripheral groove H^5 . The other or opposite discal piece L^2 , I utilize as a gear and adapt it to engage with gear operated by the engine. As such engine-gear is 20 old and well known, I omit further mention of it. To this pulley H^2 , I duly connect one end of a wire rope or chain J , preferably the former and of a size convenient to be wound on this pulley H^2 , within the groove of the latter. In 25 connection with this pulley H^2 , I provide guides of a novel adaptation, application, and location to accomplish the objects for which the pulley and rope are designed.

K indicates a bar of iron whose free end 30 is extended out beyond the plane of the adjacent side of the coal-box, substantially as shown in Fig. 3. The other end is fixed to a rear portion of the machine, preferably, as shown, by the bolt L and by the bolt L^3 . K^2 35 is a second bar parallel to the bar K , and one end is secured to the machine, preferably by the bolt L , and its free end extends out above the bar K . These bars are further secured by a link N , which is secured 40 to the bolt L^2 , and is secured to the bars by a bolt N^2 . The free ends of these bars are secured together by a bolt L^7 . The attachment of these bars K and K^2 to the flanges L^5 and L^6 and by the link N holds the latter 45 firmly in the position shown. These flanges L^5 and L^6 are fixed to the box C . Between these bars K and K^2 are located two shives or guide-pulleys M M , preferably grooved, as shown. These shives are duly journaled in 50 the bars K and K^2 and are respectively supplied with oil-boxes M^2 M^3 , whereby they are duly lubricated.

The mode in which my invention is operated is as follows: The road and traction engine heretofore described is caused to propel itself to any place desired. The great wheels G are utilized for packing down and smoothing the rough parts of roads and other places, as may be desired. The traction-engine can 55 be employed for traction purposes by connecting the thing which is to be drawn or dragged by a chain or other suitable connection to the link R at the rear end of the coal-box C . The engine being started forward, it 60 will as it proceeds draw along with it the thing thus connected to it; but there are two cases, and very important ones, when the for-

ward or backward movement of the engine is wholly unnecessary and undesirable. The first of these is when the movement of the engine would carry it over ground which ought not to be crossed by the engine or when the way is barred by rocks, marsh, or other impediments, so that the engine could not proceed. In this case whether the engine 75 when under movement would or would not have traction-power enough to draw along the thing to be drawn it is evident that it must not be moved. The second of these cases is when the resistance of the thing to be drawn 80 is greater than the traction of the engine can overcome. In both of these cases my invention becomes essentially necessary. I then operate my invention as follows: I block the great wheels G . I withdraw the locking-pin 85 H^4 from the pulley H^2 and on the other side also disconnect the wheel G there from that end of the shaft or axle H . The pulley H^2 is then rotated, usually by the engine, and the wire rope J unwound until enough of it has 90 been paid out to enable the free end of it to be hooked or otherwise connected to the article to be dragged or drawn. Such connection with the latter article having been made, the engine is set in motion and the pulley H^2 rotated 95 so as to gradually wind up the wire rope J . This it will do with great power and effect. I am enabled to plow therewith to a great depth in a macadamized street or equally rocky and hard soils. As the wire rope is wound up it is 100 guided between the two shives. When the plow or other thing to be drawn or dragged is drawn to or near to the engine or as far as desired by the wire rope and it is desired to repeat the operation, the free end of the wire 105 rope is drawn back, thereby unwinding the rope from the pulley. When it is desired to return the plow or similar implement to its first position at the end of the wire rope, (unwound,) I usually employ a horse to return 110 said implement. It is at such times that the brake I will now describe becomes of special utility. This brake consists of a shoe P and a lever P^2 , pivotally fulcrumed at P^3 to the machine by a removable fulcrum. Thus the 115 brake can be removed when not in use. The lever is bent at P^4 , so as to duly bridge the pulley H^2 . The shoe P bears against the side of the pulley H^2 near the periphery of the latter. When the wire rope is being drawn out too 120 fast, which is particularly the case when the horse feels skittish or full of life, an application of the brake to the pulley H^2 serves to hold him back and compel him to move quietly and regularly. After the work to be performed 125 by the pulley H^2 and wire rope, &c., has been accomplished the wire rope is wound up upon the pulley and the free end of the rope is fastened to the pulley.

The means for fastening the pulley constitute still another feature of my invention and are as follows: I provide a hook S , having a shank S^2 , the latter having on its free end a screw-thread S^3 . The outer rim of the pulley

is provided at convenient intervals with holes H⁵. After the wire rope J has been wound upon the pulley it becomes desirable to fasten the loose end of the rope. Thereupon 5 the shank of this hook S is passed through that hole H⁵ of the pulley-rim which is nearest the end of the rope. The end part of the rope is placed in this hook. The latter is then pressed toward the pulley. The free end of 10 the shank now projects inside the rim, and the nut S⁴ is now screwed thereon. Thus the rope's end is duly held. The revolution of the pulley as the steam-roller is moved and the axle H revolves will not unwind the rope. 15 When it is desired to use the rope, as before mentioned, I unscrew the nut, withdraw the hook, and loose the rope's end from the latter. Wherever the term "wire rope" is used I 20 desire it to be read as standing for chain or other suitable flexible means of connection.

What I claim as new and of my invention, and desire to secure by Letters Patent, is—

1. In a traction road-roller machine, the driving-axle, traction driving-wheels, located 25 concentrically thereon, one of said driving-wheels being loose upon the said driving-axle, a windlass located upon the same axle, and fixed thereto and close to said traction driving-wheel loose upon said axle, the latter 30 traction-wheel having an enlarged hub provided near its outer edge with an opening G⁸, and the windlass having an opening H³ in its side adapted to align with said opening G⁸, and a bolt for entering said openings G⁸ and 35 H³, and making the said driving traction-wheel a temporary fixture on the axle, and means for connecting at will the other traction-wheel to the axle and disconnecting the 40 said wheel therefrom, substantially as and for the purposes specified.

2. In a traction-engine, the traction driving-wheels G, and their driving-axle H, and the pulley fixed on said axle, means for connecting the pulley to said adjacent driving- 45 wheel so that the axle may drive the latter, wire rope connected to said pulley, and the flanges L⁵ and L⁶, and the bars K and K², connected to these flanges and angulated out therefrom and extended beyond the side of 50 the machine-box, substantially as and for the purposes specified.

3. In a traction-engine, the traction driving-wheels G, driving-axle H thereof, grooved 55 pulley H², fixed on said axle, the crank-piece fixed to wheel G, and having a hole G⁸, the pulley provided with a series of holes H³, adapted as the axle is rotated to come successively opposite the hole H³ in the crank-piece, a locking-pin H⁴ adapted to enter the 60 hole H³ in the crank-piece, and any one of the holes in the pulley H², wire rope connect-

ed to the pulley H², and the flanges L⁵ and L⁶ fixed on the machine-box, and the bar K connected at L² to the flange L⁶, and angulated out and away therefrom, and the bar K² connected at one end to the flange L⁶ at L and angulated out and away therefrom, and the link N, secured to the flanges L⁵ and L⁶, and to the bars K and K², and the shives M, M, located beyond the plane of the side of the 65 machine-box, and behind, and in line with the said pulley, substantially as and for the purposes specified.

4. In a traction-engine, the traction driving-wheels G, and their driving-axle H, and 75 the pulley fixed on said axle, means for connecting the pulley to said adjacent driving-wheel so that the axle may drive the latter, wire rope connected to said pulley, and the removable brake P, applied to the end (side) 80 of the pulley, substantially as and for the purposes specified.

5. In a mechanism for utilizing the axle of the road-roller, substantially as and for the purposes specified, the pulley thereon, and 85 wire rope thereof, and having holes through its rim, and the clamp S curved at one end, and having a shank S², adapted to be passed through a hole in the pulley-rim, and the shank having a screw-thread, and a nut 90 adapted to be screwed on the end of the shank, after the latter has been put in and through the hole in the pulley-rim, substantially as and for the purposes specified.

6. In a traction road-roller machine, the 95 driving-axle, traction driving-wheels, located concentrically thereon, one of said driving-wheels being loose upon the said driving-axle, a windlass located upon the same axle, and fixed thereto and close to said traction 100 driving-wheel loose upon said axle, and the windlass located between said traction-wheel and the body of the vehicle, the latter traction-wheel having an enlarged hub provided near its outer edge with an opening G⁸, and 105 the windlass having a series of openings H³, in its side next to said traction-wheel, and in a circle described from the axis of said axle as a center, each opening adapted when the windlass is turned to successively align with 110 the opening G⁸ of the traction-wheel hub, and a bolt for entering said opening and the opposite opening H³ in the windlass, for compelling the traction-wheel to rotate, and means for connecting and disconnecting the 115 driving-axle and the traction-wheel on the other side of the machine, substantially as and for the purposes specified.

WILLIAM SALWAY.
